UNITED STATES PATENT OFFICE

2,081,105

AIR CIRCULATING APPARATUS

Frank C. Reynolds, New York, and Walter H. Kirchheim, Mount Vernon, N. Y., assignors to American Radiator Company, New York, N. Y., a corporation of New Jersey

Application October 2, 1935, Serial No. 43,206

2 Claims. (Cl. 98—94)

This invention relates to ventilating devices and more particularly to the type of ventilating device which is adapted to be installed in window openings of rooms and which operates to force 5 fresh filtered air into the room and/or to exhaust the room air to the outdoors.

An object of our invention is to provide a ventilating device which is of improved construction and arrangement of parts and which is provided with an improved form of casing, pleasing in appearance and requiring very little more room space, if any, than the usual window sill.

Other objects are to provide a casing structure which is water tight even though a portion 15 thereof extends outside of the window and is exposed to the elements, a casing structure so formed that the interior thereof is readily accessible for the purpose of removing and replacing filters and for oiling and making minor repairs 20 to the air circulating apparatus installed therein; and lastly a casing which provides for an effective sealing engagement between the sill rail of a window sash and the top of the casing, so that air will flow only through the casing.

25 The invention consists in the novel construction and combination of parts, to be more fully described hereinafter, and the novelty of which will be particularly pointed out and distinctly claimed.

30 In the accompanying drawings, to be taken as a part of this specification, we have fully and correctly illustrated two preferred embodiments of our invention, in which drawings:

Fig. 1 is a perspective view showing a ventilating device constructed in accordance with the present invention, as installed in the conventional window of a room:

Fig. 2 is a transverse vertical section of the apparatus shown in Fig. 1, the section being taken 40 on the line 2—2 of Fig. 1:

Fig. 3 is a transverse vertical section similar to Fig. 2, and showing a modified form of our invention:

Fig. 4 is a plan view of the device shown in Fig. 3, showing the rear cover as raised for the purpose of exposing the interior thereof.

In accordance with one preferred embodiment 50 of our invention, we provide a ventilating device which is adapted to be positioned longitudinally across an opening defined by the sill rail of a partially raised window sash and the window sill. The device comprises a casing structure including a top wall divided longitudinally into a front cover portion fixedly secured to the remaining portions of the casing and adapted to be disposed

on the room side of the window sash, and a rear cover portion hingedly connected at its rear edge to the rear portions of the casing so that it pivots about an axis extending lengthwise of the casing and substantially parallel to the plane of the 5 window sash. We also provide a sealing means along the forward edge of the rear cover portion, against which the lower part of the sill rail of the window sash engages so as to prevent the infiltration of outside air or sound and to prevent 10 the escape of room air, except through the casing structure. The casing is provided with a rear inlet opening, a front outlet opening in the forward portions thereof, and with means in the interior thereof for effecting a positive movement 15 of air through the casing. In the preferred embodiment of our invention, there is arranged a filter for eliminating foreign particles entrained in the incoming outside air.

By reason of this construction and arrangement, a ventilating device of relatively large capacity may be provided and it will only be necessary for a small portion of the casing to extend into the room, thereby providing a ventilating device which occupies a minimum of 20 room space, one which is unoffensive to the eye, and one which offers a minimum of interference to the passage of light into the room. The rear hinged cover portion may be readily opened upon raising the window sash 25 to permit the insertion or replacement of the filter and to permit minor repairs and oiling and greasing of the mechanical parts of the ventilator.

Referring now in detail to the construction 35 illustrated and first to Figs. 1 and 2, the reference numeral 10 indicates a ventilating device which is mounted in the opening defined by a partially raised window sash and the window sill of a conventional window. The window sill 40 is indicated by the reference numeral 11, the jambs by the reference numeral 12 and a sash by the reference numeral 13. The sash 13 is slidably mounted in the jambs 12 and includes a lower sill rail 14 which engages the upper 45 surface of the ventilating device 10. The space between the ends of the ventilating device and the jambs 12 may be filled by suitable blocks 50 15 which prevent infiltration of outside air or the escape of room air around the ends of the ventilator. The blocks 15 are arranged in the plane of the sash 13 and are provided along their upper edges with sealing material 16 such as felt or rubber, for engagement by the sill 55

rail 14 when the sash is lowered to the position shown in Fig. 1.

The ventilator comprises a casing 17 including a bottom wall 18 mounted on the window sill 11, a rear wall 19 having an inlet opening 20 for the admission of fresh outside air, a front wall 21, and end walls 22 suitably bevelled at the front as indicated at 23, to give a pleasing appearance. The casing 17 also comprises a top wall 24 divided longitudinally at 25 into a front cover portion 26 rigidly secured to the front and end walls 21 and 22 respectively, and a rear cover portion 27 hingedly connected at its rear edge by means of hinges 28 to the rear wall 19 of the casing.

A motor-blower unit 30 may be mounted within the casing and serves to draw fresh air from the outside into the casing through the inlet opening 20, and to force such air into the room through grille-covered openings 31 in the front cover portion 26 of the top wall 24. Disposed behind the motor-blower unit 30 and on the down-stream side of the inlet opening 20, is a filter 32 which is removably mounted in vertically arranged guides 33 and extends lengthwise across the casing. The filter operates to remove any entrained foreign particles in the air entering the ventilator through the inlet opening 20.

It is to be noted that, while we have shown a motor-blower unit which functions only to bring in fresh air to the room, our invention in all of its aspects is not to be considered as being so limited, for the unit may be constructed to exhaust air from the room, or, both to bring in and to exhaust air.

A channel-shaped member 35 extends along the forward edge of the hinged cover portion 27 and is fixed thereto by any suitable means, such, for example, as by spot welding. A sealing material 36 such, for example, as felt, rubber, or the like, is arranged within the channel 35 and provides a sealing surface against which the sill rail 14 of the sash engages and prevents the passage of air or sound from the outside into the room. As can be seen from an examination of Fig. 2, the rear cover portion 27 slopes downwardly and rearwardly, and this, in conjunction with the upright flanges of the channel 35 and the sealing engagement between the sill rail and the material 36, prevents the collection of rain water and the like on the cover portion 27 and the leakage of such water past the channel into the room.

From the above description it will be readily appreciated that, in order to remove or replace the filter 32, all that is necessary is to raise the sash 13 and open the rear hinged cover portion 27. By reason of the fact that the channel 35 is secured to the rear cover at points spaced from the hinged connection, the lower sill rail 14, when in engagement with the sealing material 36 carried by the channel, serves to hold the rear cover tightly in position on the casing, thereby preventing the leakage of water, snow, etc., from the outside into the casing. The rear cover 27 is also provided with a downwardly extending flange 37 at each end thereof, which overlap the end walls 22 of the casing and thereby serve to render the casing more water tight.

In Figs. 3 and 4 of the drawings, we have illustrated a ventilating device in which is included substantially the same casing features as those of the previously described modification of Figs. 1 and 2. The ventilating device comprises a casing 58 including a bottom wall 51, secured

to the window sill 11a, a rear wall 52 having an inlet opening 53, end walls 54, a front wall 55 having an outlet opening 56 in which is arranged adjustable louvers 57 for directing the air to different portions of the room, and a top wall 58 divided longitudinally adjacent the center line of the casing into a front cover portion 59 rigidly secured to the casing and a hinged rear cover portion 60 connected by hinges 61 with the rear wall 52 of the casing.

The front cover portion 59 is also provided with spaced air outlet openings 62 and 63 respectively, and a louver 64 is hingedly mounted within each of the openings 62 and 63 and serves to direct the air from the casing upwardly and towards the window sash 13a, if desired.

The end walls 54 are offset as indicated at 65 and vertical channels 66 are arranged at the points of the offsets and are secured to the end walls for the purpose of receiving the vertical ends of filler blocks 15a, the latter filling the space between the ends of the casing and the sides of the window frame, the same as the blocks 15 in Fig. 1.

Arranged within the casing, is a motor-blower unit 70, comprising a motor 71 and a blower 72 arranged at each side of the motor. Each of the blowers 72, comprises a housing 73 having inlet openings communicating with the inlet 53 of the casing through an inlet chamber 74 and an outlet opening 75 communicating through an air outlet chamber 76, with the louver controlled openings 56, 62, and 73 in the front wall and the top wall, respectively.

As in the previously described modification, a filter 77 is removably supported in vertically arranged guides 78 in the casing adjacent the inlet opening 53, and the rear cover portion 60 is provided with a sealing means 79 against which the sill rail 14a of the window sash 13a engages. The sealing means is in the form of a Z bar 80 extending longitudinally of the top of the casing for the length thereof and comprising a flange 81 suitably secured, as by means of spot welding, to an upwardly extending flange 82 on the forward edge of the cover portion 60. Sealing material 83 in the form of felt, rubber, or the like is suitably secured to a horizontal flange 84 of the Z bar and serves, when the sill rail 14a is in engagement therewith, to prevent the passage of sound and/or air from the outside into the room, except through the casing. The horizontal flange 84 of the Z bar 79, the filler blocks 15a, and the channels 66 are all arranged in substantially the same plane as the window sash so that when the window sash is lowered, an effective closure of the window opening is effected.

As in the previously described modification, the hinged rear cover portion carrying a sealing means, against which the sill rail 14a is lowered, provides ready accessibility to the interior of the casing for replacing filters, oiling the mechanical parts, and making minor repairs. Also, the hinged rear cover portion 60 slopes downwardly and rearwardly, and, in conjunction with the flange 81 and sealing material 83, provides for readily shedding rain water and the like from the exposed portions of the ventilator and for preventing leakage of such water into the room.

What we claim and desire to secure by Letters Patent is as follows:

1. A ventilating device for circulating air in a room and of the type adapted to be positioned longitudinally across an opening defined by a sill rail of a partially raised window sash and

5 a window sill, comprising a casing structure including a top wall divided longitudinally into a front cover portion adapted to be disposed on the room side of the window, and a rear cover portion adapted to be arranged outside of the window and being hingedly connected along its rear edge to the rear portions of the casing, the rear cover portion sloping downwardly and rearwardly from the longitudinal dividing line to the 10 rear edge thereof so as to provide for shedding rain water and the like from the top of the casing, and means carried by the forward part of the rear cover portion and extending longitudinally of said casing adjacent the dividing line and providing an engaging and sealing surface 15 between the sill rail and the casing.

20 2. A ventilating device for circulating air in a room and of the type adapted to be positioned longitudinally across an opening defined by a sill rail of a partially raised window sash and a window sill, comprising a casing structure including a top wall divided longitudinally into a

front cover portion adapted to be disposed on the room side of the window, and a rear cover portion adapted to be arranged outside of the window and being hingedly connected along its rear edge to the rear portions of the casing, the rear cover portion sloping downwardly and rearwardly from the longitudinal dividing line to the rear edge thereof so as to provide for shedding rain water and the like from the top of the casing, and means carried by the forward part of the rear cover portion and extending longitudinally of said casing adjacent the dividing line and providing an engaging and sealing surface between the sill rail and the casing, said means comprising an upright flange member arranged adjacent to and extending in the same direction as the longitudinal dividing line and a longitudinally extending strip of sealing material lying adjacent the flange and interposed between the casing and the sill rail. 15
